K. SCHLESINGER

UNITED STATES PATENT OFFICE

2,054,884

PHOTO-AMPLIFIER TUBE

Kurt Schlesinger, Berlin, Germany

Original application February 19, 1934, Serial No. 711,915. Divided and this application January 30, 1935, Serial No. 4,058. In Germany February 20, 1933

2 Claims. (Cl. 250—27.5)

The invention relates to photo-electric arrangements for television purposes including a photo-electric tube and an amplifier connected thereto, and is a division of my application Serial No. 5 711,915 filed Feb. 19, 1934.

It is the object of the present invention to combine both arrangements and such as to have a unitary device. The known arrangements of this kind have a relatively high detrimental capacity in the order of more than 5.5×10^{-6} mf.

The effect of the detrimental capacity of a photo-tube on the reproduction of the high frequencies is known per se.

It has already been proposed to combine the photo-tube with the amplifier tube to form one structural unit. In these arrangements, however, the cathode of the photo-tube has always been connected with the grid of the amplifier. As amplifiers there have been employed tubes with relatively high anode reaction effect.

20 It is not possible in these previously known arrangements to reduce the capacity of the photo-tube arrangement to less than 5.5×10^{-6} mf. In order to keep sufficiently small the frequency dependency resulting in the case of a 25 capacity of this kind, the ohmic resistance on which the photo-tube acts must be made very small (approximately 5000 ohms in the case of a 180-line image). When using such a small anode resistance, the potentials produced by the photo-tube are not great enough in comparison to the natural noise of the amplifier, so that the 30 production of television images with a large number of lines (for example 180 lines and more) is practically impossible with arrangements of 35 this nature.

The object of the invention is a photo-tube arrangement, the detrimental capacity of which is considerably less than 5.5×10^{-6} mf. (for example amounts to approximately 2 cm.), and 40 which, therefore, permits of the production of television images of the kind in question without special, complicated means (carrier current method).

According to the invention the photo-tube is 45 arranged in the upper part of an evacuated container and an amplifier stage is arranged in the lower part of this container. A reflector is mounted between said both parts.

The working resistance may, in accordance with 50 the invention, be provided in the tube itself, and owing to the reduction of the detrimental capacities may be selected to be still larger. The same, for example, with a drop of merely 8% (in a 180-line image) may amount to 20,000—

25,000 ohms. Practically, therefore, as set forth above, a resistance of approximately twice the size, i. e., up to approximately 50,000 ohms, may be employed, so that the effectiveness of the connection system is nearly ten times greater than 5 that of the previously known arrangements.

From these known arrangements that according to the invention differs fundamentally by the fact that both the capacity of the photo-cathode (which is practically equal to the radius of the 10 sphere of the tube and, therefore, cannot be made smaller than approximately 2 cm.) as well as the reaction capacity of the amplifier tube do not make a part of the detrimental capacity, and that the remaining grid capacity is substantially 15 smaller than in the case of the known arrangements.

A possible form of embodiment is illustrated in the drawing, in which

1 is the common vessel, 2 the photo-electric layer provided on the upper part of the wall of the vessel with the lead 4, and 3 a window aperture, through which the light falls on to the photo-electric layer 2. In the lower part of the bulb there is provided the amplifier system, which comprises the grid 5, the indirectly heated cathode 6, the screening grid 7, the anode 8 and the photo-tube anode resistance 10. All electrodes may conveniently be secured to a support 9 consisting of insulating material. The end of 20 the grid 5 located in the upper space of the vessel acts as the anode of the photo-tube. At this end there may conveniently be provided a cap 11, which contains the metal for the production of the photo-layer 2, or if desired a suitable 25 reaction mixture for developing this metal. In accordance with the invention the diameter of 30 this cap may be made very small.

Naturally it is also possible to mount the cap 35 completely separate from the grid, viz., in such a fashion, that it does not form a part of the electrical system.

The cap may be filled, for example, with a mixture of bichromate of caesium and silicon. If the 40 cap is heated to the reaction temperature of the mixture in the manner known per se for example by means of eddy currents, pure metallic caesium is developed, which is deposited in the upper part of the bulb. The part of the bulb intended for the formation of the photo-layer may preferably 45 be furnished with a suitable preliminary coating, for example of metallic silver or silver oxide.

In accordance with the invention, there may be 50 provided above the glass support 9 a reflector 12, which is composed for example of metallized mica 55

and does not require to be earthed. This reflector causes in itself reflection of the light and, particularly if the window 3 is provided centrally over the axis of the tube, results in a considerably better utilization of the entering light.

It is desirable in accordance with the invention at first to place the amplifier system in an entirely operable condition (outgassing of the electrodes, atomization of highly emissive metal on 5 to the cathode or forming of the oxide cathode), and not until then—in the well evacuated bulb—to atomize the metal (for example caesium) serving for the production of the photo-electric layer.

For many purposes of use it is desirable to provide several or all of the after-connected amplifier systems of the cascade in the same bulb, as in 10 this manner the total capacity of the cascade can be considerably reduced.

I claim:

20 1. A photo-amplifier tube comprising an evacuated container provided with a press portion, a photo-electric layer coating the inner wall of the upper part of the said container, said coating being provided with a window, a cathode, an 15 anode, a control grid and a screening grid in the lower part of said container, a screen provided with an opening mounted between said electrodes and said photo-electric layer, said 20

grid projecting through said opening of said screen into said upper part of said container, a small cap containing a reaction mixture, said cap being attached to said projecting end of said grid, and connection means for all of said electrodes, said connection means including supporting means for said anode, cathode and said grids.

2. A photo-amplifier tube comprising an evacuated container provided with a press portion, a photo-electric layer coating the inner wall of the upper part of said container, said coating being provided with a window, a cathode, an anode, a control grid and a screening grid in the lower part of said container, a screen provided with an opening mounted between said electrodes and said photo-electric layer, said control grid projecting through said opening of said screen into said upper part of said container, a small cap containing a reaction mixture, said cap being attached to said projecting end of said grid, and connection means for all of said electrodes, said connection means including supporting means for said anode, cathode and said grids, a working resistance of the order of 50,000 25 ohms connecting said cathode and said control grid said resistance having low natural capacity.

KURT SCHLESINGER.
